(57) **CLAIM**

The ornamental design for a data cable as shown and described.

DESCRIPTION

FIG. 1 is a front, right, and top perspective view of a data cable, showing my new design;

FIG. 2 is a rear, left, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective view thereof, shown in an alternate configuration.

The data cable is shown with a symbolic break in its length, shown with dot-dot-dash broken lines in the drawing disclosure. The appearance of any portion of the article between the two dot-dot-dash break lines, and the dot-dot-dash broken lines themselves, form no part of the claimed design. All other broken lines depict portions of the data cable that form no part of the claimed design.
